UNITED STATES PATENT OFFICE.

CARL ROB. BLOMBERG, OF CHICAGO, ILLINOIS.

DESIGN FOR A WATCH-FOB.

46,392.

Specification for Design.

Patented Sept. 15, 1914.

Application filed April 17, 1914. Serial No. 832,645. Term of patent 3½ years.

To all whom it may concern:

Be it known that I, CARL R. BLOMBERG, a subject of the King of Sweden, residing at Chicago, in the county of Cook and State of Illinois, have invented a new, original, and ornamental Design for Watch-Fobs, of which the following is a specification, reference being had to the accompanying drawing, forming a part thereof.

Figures 1 and 2 are respectively front and back views of a watch fob, showing my new design.

I claim:

The ornamental design for a watch fob, as shown.

CARL ROB. BLOMBERG.
